United States Patent

Des. 236,036
Patented July 22, 1975

236,036

HANDBAG

Clarence V. Tibbs, Knoxville, Tenn., assignor to Balls 'n' All, Inc., Knoxville, Tenn.

Filed Aug. 24, 1973, Ser. No. 391,301

Term of patent 14 years

Int. Cl. D3—01

U.S. Cl. D87—3 F

Fig. 1.

Fig. 2.

Fig. 3.

FIG. 1 is a top plan view of a handbag showing my new design, a portion of the handle being broken away for convenience of illustration;

FIG. 2 is a front elevation view; and

FIG. 3 is a left side elevation view.

I claim:

The ornamental design for a handbag, as shown and described.
